(57) **CLAIM**

The ornamental design for a grip device for handling work pieces, as shown and described.

DESCRIPTION

FIG. 1 is a front elevational view of a grip device for handling work pieces showing my new design, the rear elevational view being a mirror image thereof;

FIG. 2 is top plan view thereof;

FIG. 3 is a bottom plan view thereof; and,

FIG. 4 is a bottom front perspective view thereof.

The broken lines depict portions of the grip device in which the design is embodied that are not considered part of the claimed design.
